J. W. MADDEN.

STOVE DAMPER.

APPLICATION FILED DEC. 31, 1919.

1,356,383.

Patented Oct. 19, 1920.

Inventor

JOHN W. MADDEN,

Geo. P. Himmel
Attorney

UNITED STATES PATENT OFFICE.

JOHN W. MADDEN, OF PITTSFIELD, MASSACHUSETTS.

STOVE-DAMPER.

1,356,383.

Specification of Letters Patent. Patented Oct. 19, 1920.

Application filed December 31, 1919. Serial No. 348,539.

To all whom it may concern:

Be it known that I, JOHN W. MADDEN, a citizen of the United States, residing at Pittsfield, in the county of Berkshire and State of Massachusetts, have invented certain new and useful Improvements in Stove-Dampers, of which the following is a specification.

This invention relates to the dampers employed in smoke flues of various kinds, more particularly to the smoke flues of kitchen ranges and stoves, and has for one of its objects to provide a simply constructed device whereby the damper may be actuated 10 from any required distance and in any required direction.

With these and other objects in view, the invention consists in certain novel features of construction as hereinafter shown and 20 described and then specifically pointed out in the claims, and in the drawings illustrative of the preferred embodiment of the invention—

Figure 1, is a front elevation of a portion 25 of the upper part of a conventional kitchen range and a contiguous portion of the smoke flue of the range, including the damper, with the improved damper actuating apparatus applied, a portion of the range being broken away to show one of the coupling devices.

Fig. 2, is a side view of the parts shown in Fig. 1, with the portion of the range in transverse section on line 2—2 of Fig. 1.

Fig. 3, is a plan view, with the smoke flue in transverse section.

Fig. 4, is an enlarged detached perspective view of the coupling block and its combined set screw and coupling pin.

Fig. 5, is an enlarged perspective view of the bearing block whereby the operating shaft is coupled to the range or other support.

Fig. 6, is an enlarged detached perspective view of the operating shaft, the coupling rod or crank arm, and the stop pin.

The improved device may be readily adapted without material structural change to dampers of various forms and sizes and 50 it is not desired to limit the invention in this respect, but for the purpose of illustration the device is shown applied to the ordinary damper of the smoke flue associated with a kitchen range, 10 representing a portion of the flue, 11 the damper, having the usual turning knob 12, and 13 a por-

tion of the back or rear guard which rises above the usual warming oven of a kitchen range.

The improved apparatus includes a clip 60 device 14 bearing around the knob 12 and held immovably thereon by a clamp screw 15. One arm of the clip is directed in advance of the other arm and pivotally united at 16 to the upper end of a rod 17.

A second clip device is also provided to be detachably connected to the part 13 of the range or other support, and includes a body 18 having a transverse aperture to rotatably receive an operating shaft 19. 70

The body 18 is forked at the lower end to bear over the member 13 and is secured in place by a clamp screw 20.

The body 18 may be modified to any required extent to enable it to be clamped to 75 other forms of support than the member 13.

The block 18 is also provided with a lateral recess or two-way slot 21 communicating with the aperture for the shaft 19, as shown in Fig. 5, and inserted in the shaft 80 is a stop pin 22 which extends through the recess, to limit the movement of the shaft.

Slidable on the rod 17 is a block 23 having a threaded transverse aperture to receive the threaded end of a bent pin 24, the pin 85 thus serving as a set screw to hold the block 23 in adjusted position on the rod 17.

Attached to the shaft 19 is a crank arm 25 having means such as an eye 26 at its free end to engage the pin 24. 90

The stop 22 and the crank arm 25 are detachably coupled to the shaft 19, for instance by screw threads, as shown, so that they can be detached to enable the shaft to be inserted in its seat in the bearing clip 18, 95 and the pin 22 engaged with the shaft through the recess 21 and the crank arm 25 connected to the shaft and to the pin 24.

The shaft 19 is provided with a turning knob 27, and may be of any required length, 100 to locate the knob 27 at any convenient point.

It will be obvious that with a device thus constructed and applied, the damper 11 can be opened or closed or partly opened by simply rotating the shaft 19 by its knob 27. 105 The stop pin 22 when in the bottom of the recess 21 holds the shaft from being turned a sufficient distance to move the damper beyond its horizontal or closed position, and when at the opposite end of the recess the 110 pin prevents the shaft from moving the damper beyond its full open position.

The dampers of the smoke flues of ranges and the like are usually located at too high a point from the floor and at too great a distance from the body of the range to be conveniently reached, but with the simple attachment above described, the damper can be actuated from any desired distance or direction from the flue as will be obvious, by lengthening or shortening the shaft 19 and 10 the rod 17.

The preferred embodiment of the invention is disclosed in the drawings and set forth in the specifications, but it will be understood that any modifications within 15 the scope of the claims may be made in the construction without departing from the principle of the invention or sacrificing any of its advantages.

Having thus described the invention, what 20 is claimed as new is:—

1. A device of the class described comprising a bearing member adapted to be connected to a support and having a recess communicating with the interior thereof, 25 a shaft rotative in said bearing member and having a crank arm directed laterally therefrom, a stop pin extending from said shaft and through said recess, a clip device adapted to be clamped to the turning element of 30 a damper, and a rod connected respectively

to said clip device and to said laterally directed crank arm.

2. A device of the class described comprising a bearing member adapted to be connected to a support and having a recess 35 communicating with the interior thereof, a shaft rotative in said bearing member and having a crank arm directed laterally therefrom, a stop pin extending from said shaft and through said recess, and connecting 40 means extending from said laterally directed crank arm and adapted to be coupled to the turning element of a damper.

3. A device of the class described comprising a bearing member adapted to be connected to a support, a shaft rotative in said bearing member and having a crank arm directed laterally therefrom, a clip device adapted to be clamped to the turning element 45 of a damper, a rod pivotally connected to 50 said clip device, a block slideable on said rod, a combined set screw and pin engaging said block and operating to adjustably clamp said block to said rod, said crank arm being movably coupled to said combined set screw and 55 pin.

In testimony whereof I affix my signature hereto.

JOHN W. MADDEN.
